GOLF CLUB HEAD

John Warren Gillon, San Mateo, Calif.

Application January 23, 1956, Serial No. 39,874

Term of patent 14 years

(Cl. D34—5)

Fig. 1

Fig. 2

Fig. 3

Fig. 1 is a top plan view of a golf club head, showing my new design;

Fig. 2 is a side elevational view thereof, the opposite side having substantially the same appearance; and

Fig. 3 is an end elevational view thereof.

In the drawing, the hatching on the top of the club head indicates color.

I claim:

The ornamental design for a golf club head, as shown and described.
